UNITED STATES PATENT OFFICE.

FREDERICK MAYER, OF NEW YORK, N. Y.

DESIGN FOR A SWEATER.

41,292.

Specification for Design.

Patented Apr. 4, 1911.

Application filed September 20, 1910. Serial No. 582,944. Term of patent 3½ years.

To all whom it may concern.

Be it known that I, FREDERICK MAYER, a citizen of the United States, residing in the city of New York, borough of Manhattan, in the county and State of New York, have invented a new, original, and ornamental Design for a Sweater, of which the following is a specification, reference being had to the accompanying drawing, forming a part thereof.

The figure is a perspective view of a sweater, illustrating my new design.

I claim:

The ornamental design for a sweater, as shown.

FREDERICK MAYER.

Witnesses:

W. W. HOLT,
PHILIP D. ROLLHAUS.

Copies of this design may be obtained for five cents each, by addressing the "Commissioner of Patents, Washington, D. C."
